(57) **CLAIM**

The ornamental design for an apparatus for sleep information detection, as shown and described.

DESCRIPTION

FIG. 1 is a top, front and left side perspective view of apparatus for sleep information detection with a detection module and a stand for the detection module;

FIG. 2 is a front elevation view of the apparatus for sleep information detection of FIG. 1;

FIG. 3 is a rear elevation view of the apparatus for sleep information detection of FIG. 1;

FIG. 4 is a top, front and left side perspective view of the detection module of FIG. 1;

FIG. 5 is a top, rear and right side perspective view of the detection module of FIG. 4;

FIG. 6 is a front elevation view of the detection module of FIG. 4;

FIG. 7 is a rear elevation view of the detection module of FIG. 4;

FIG. 8 is a top, front and left side perspective view of a version of a stand of the apparatus for sleep information detection of FIG. 1 such as for a detection module;

FIG. 9 is a front elevation view of the stand of FIG. 8; and, FIG. 10 is a rear elevation view of the stand of FIG. 8.

The broken lines immediately adjacent to the shaded areas represent the bounds of the claim, while all other broken
